UNITED STATES PATENT OFFICE.

JOHN B. HADAWAY, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TACK-PULLING MACHINE.

1,285,135.

Specification of Letters Patent. Patented Nov. 19, 1918.

Application filed September 1, 1917. Serial No. 189,318.

To all whom it may concern:

Be it known that I, JOHN B. HADAWAY, a citizen of the United States, residing at Swampscott, in the county of Essex and 5 State of Massachusetts, have invented certain new and useful Improvements in Tack-Pulling Machines; and I do hereby declare the following to be a full, clear, and exact 10 description of the invention, such as will enable others skilled in the art to which it app- pertains to make and use the same.

The present invention relates to tack pulling machines and more particularly to machines of this type employed for removing 15 the side tacks from a lasted boot or shoe.

It is desirable that machines of this type shall operate with certainty and rapidity to remove the tacks which hold the lasted upper in place without tearing or otherwise 20 damaging the upper of the shoe.

An object of the invention is to provide a tack pulling machine having an improved construction and mode of operation which insures the engagement and removal of the 25 tack without tearing the upper. A further object of the invention is to provide improved mechanism for actuating the tack pulling jaws in a manner to permit the release of the shoe upper if the latter is accidentally caught between the jaws.

With the above objects in view the various features of the invention consist in certain novel features of construction, combinations and arrangements of parts hereinafter de- 35 scribed and claimed, the advantages of which will be obvious to those skilled in the art from the following description.

In the preferred form of the invention shown in the accompanying drawings, 40 Figure 1 represents a side elevation of a tack pulling machine embodying the features of the invention; Fig. 2 is a plan view of the machine with the casing cut away to show the mechanism for actuating the tack 45 pulling jaws; Fig. 3 is a detail illustrating a portion of the construction for actuating the tack pulling jaws; Fig. 4 is a detail illustrating a cross section of the jaws and co- operating work supports taken upon the 50 line 4—4 of Fig. 1; and Fig. 5 is a partially diagrammatic view illustrating the paths in which the two tack pulling jaws are moved.

According to the present invention the tack is removed by a pair of coöperating

jaws which are actuated in a manner to insure the engagement and removal of the tack without defacing or otherwise damaging the upper of the shoe in any manner. The mechanism for actuating the tack pulling jaws is simple in construction and 60 efficient in its mode of operation, permitting the jaws to be operated at the highest rate of speed consistent with the proper engagement of the tacks.

In the simplest and most efficient form of 65 the invention which has yet been devised the jaws are secured upon the outer ends of two supporting levers which are pivotally supported upon a rocker arm between their ends. The rocker arm is oscillated to move 70 the jaws bodily toward and from the shoe through a crank motion and the jaw supporting levers are oscillated about the pivotal connection with the rocker arm to open and close the jaws through a pair of 75 cams disposed upon opposite sides of the crank and connected directly to the ends of the levers.

In the illustrated embodiment of the invention a pair of coöperating tack pulling 80 jaws 10 and 11 are secured, respectively, to jaw supporting levers 13 and 14 which are pivoted at 15 to a rocker arm 16 depending from an oscillatory shaft 17 journaled in oppositely disposed bearings 18 formed in the 85 frame of the machine. As shown clearly in Fig. 3 the levers 13 and 14 are loosely fulcrumed upon a shaft 19 secured at its opposite ends in the two parts 20 and 21 of the rocker arm 16. This construction causes 90 the levers to be moved bodily with the rocker arm and at the same time permits an independent oscillation of the levers about the pivotal connection with the rocker arm. The rocker arm 16 is actuated by a connecting rod 23 through an extension of the members 20 and 21 extending beyond the shaft 17 and connected with the rod 23 through a pin 24. The connecting rod 23 is actuated by a crank motion which in the illustrated embodiment of the invention consists of an eccentric 25 secured to the driving shaft 26 and embraced by an eccentric strap 27 secured to the end of the connecting rod 23. This construction through the proper oscillations imparted to the rocker arm 95 serves to move the jaws bodily toward and from the shoe. The opening and closing 100 105

movements to engage with and release a tack are imparted by a pair of suitably designed cams formed in the adjacent faces of cam disks 28 and 29 which are secured to the shaft 26 upon opposite sides of the eccentric 25 and are connected to the levers 13 and 14 through cam rolls 30 and 31 journaled upon the ends of the levers. It may be observed that this mechanism forms an extremely simple and compact construction for imparting the proper movements to the tack pulling jaws.

The tacks are located in operative relation to the pulling jaws by adjustable work supports 33 and 34 which coöperate to form a tack guiding throat for properly locating the tack between the pulling jaws, the movement of the tack across the jaws being limited by a transverse abutment 35. In addition to acting as work supports for properly locating the tack with respect to the pulling jaws the members 33 and 34 also serve as guards to hold down the shoe upper upon opposite sides of the line of tacks.

In order to augment the protection afforded the shoe upper by the guards and to insure against any liability of the upper being defaced or injured by the pulling jaws, the present mechanism is designed to cause the release of the upper by the jaws should the latter accidentally engage the upper between them. To this end a movement of separation is imparted to the jaws after the engagement and partial removal of the tack, which is sufficient to release the upper from between the jaws if the upper is accidentally engaged thereby. In machines of this character employed for the removal of projecting lasting tacks the jaws ordinarily grip the shank of the tack below the head and when separated to release the upper the jaws slide freely along the shank and subsequently engage with the head on a different point upon the shank to complete the removal of the tack from the shoe. In the specific embodiment of the invention shown in the drawings the movement of separation is imparted to only one of the jaws. As shown clearly in Fig. 5 the path of the tack pulling movement imparted to one of the jaws is recessed to move the jaw away from the coöoperating jaw sufficiently to permit the release of the upper if the latter is engaged therebetween. This recess is located between the ends of the path so that the two jaws subsequently close upon the tack to complete the removal.

In order to facilitate the engagement of certain of the lasting tacks which may be embedded in the folds of the upper, more especially the toe portion of the shoe, and to permit the freer manipulation of the shoe at certain times, the work support 33 is conveniently arranged to be elevated, permitting the shoe to be rocked about the work support 34. To this end the work support

33 is secured to the lower end of a slide 40 supported in inclined ways 41 formed in the frame and actuated by a toggle consisting of a lever 43 fulcrumed upon the frame at 44 and a short link 45 connecting the slide 40 and the adjacent end of the lever 43. The opposite free end of the lever 43 is connected to a treadle rod 46 which is normally elevated by a spring (not shown). The elevation of the treadle rod normally maintains the work support in the position shown in Fig. 1 of the drawings. The upward movement of the treadle rod 46 normally moves the work support 33 into the position shown in Fig. 1, which position is determined by engagement of the adjacent faces of lugs 47 and 48, formed, respectively, upon the lever 43 and the link 45. This construction serves to unyieldingly maintain the work support in the position shown in Fig. 1, the depression of the treadle rod 46 breaking the toggle and serving to elevate the work support sufficiently to permit rocking the shoe about the stationary work support 34.

The driving shaft 26 is provided with the usual tight and loose pulleys 50 and 51 which are selectively rotated through a driving belt 52 controlled by a belt shifting cage 53 supported by a bracket 54 secured to one end of a sliding shift rod 55.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A tack pulling machine, having in combination, a rocker arm, a pair of levers fulcrumed upon the rocker arm, a tack pulling jaw supported upon the end of each lever, a rotary cam connected to the opposite end of each lever for oscillating the lever about its fulcrum, and a crank actuating mechanism for oscillating the rocker arm.

2. A tack pulling machine, having in combination, a rocker arm, a pair of crossed levers fulcrumed intermediate their ends upon the rocker arm, tack pulling jaws supported upon the adjacent ends of the levers, a rotary cam operatively connected to the opposite end of each lever for oscillating the levers to open and close the jaws, and means for oscillating the rocker arm.

3. A tack pulling machine, having in combination, a rocker arm, a pair of levers fulcrumed upon the free end of the rocker arm, tack pulling jaws supported upon adjacent ends of the levers, mechanism for oscillating the levers to open and close the jaws, an extension projecting from the rocker arm, a rotary crank and a connecting rod secured at

its opposite ends to the crank and to the extension for causing the latter to be actuated by the crank.

4. A tack pulling machine, having in combination, a rocker arm, a pair of levers fulcrumed between their ends upon the rocker arm, tack pulling jaws supported upon the adjacent ends of the levers, a shaft, a pair of cam disks secured to the shaft, connections between the inner face of each cam disk and one of the levers for oscillating the levers, and crank actuated mechanism supported upon the shaft between the cam disks and connected with the rocker arm.
- 10 5. A tack pulling machine, comprising a tack pulling jaw, mechanism for actuating the jaw to engage and remove the tack, a pair of work supports engaging with the shoe upon opposite sides of the tack, and means for removing one of the supports from engagement with the shoe to permit the latter to be rocked about the coöperating support.
- 15 6. A tack pulling machine, comprising a tack pulling jaw, mechanism for actuating the jaw, a pair of work supports engaging with the shoe upon opposite sides of the tack, a slide to which one of the supports is secured and means under the control of the operator for actuating the slide to withdraw the support from engagement with the shoe.

7. A tack pulling machine, comprising a tack pulling jaw, mechanism for actuating the jaw, a pair of work supports engaging with the shoe upon opposite sides of the tack, means for locking one of the work supports in operative position, and means under the control of the operator for withdrawing the work support into an inoperative position when desired.

40 8. A tack pulling machine, having in combination, a pair of tack pulling jaws, and actuating mechanism for the jaws constructed and arranged to move the latter from the point of engagement with the tack in paths so shaped that the jaws first grip and partially remove the tack, next release the tack while continuing to move lengthwise of the tack, and finally grip the tack and complete the removal thereof from the shoe.

45 9. A tack pulling machine, having in combination, a pair of tack pulling jaws, and actuating mechanism for the jaws constructed and arranged to move the latter from the point of engagement with the tack in a direction to pull the tack and to impart a relative movement of separation to the jaws prior to the completion of the tack pulling movement sufficient to permit the release of the upper from between the jaws.

JOHN B. HADAWAY.
